UNITED STATES PATENT OFFICE.

CLIFFORD H. OAKLEY, OF TRENTON, NEW JERSEY.

DESIGN FOR RUBBER BINDING FOR MATTING ENDS OR SIMILAR ARTICLES.

40,863.

Specification for Design.

Patented Sept. 6, 1910.

Application filed June 16, 1910. Serial No. 567,338. Term of patent 7 years.

To all whom it may concern:

Be it known that I, CLIFFORD H. OAKLEY, a citizen of the United States, residing in the city of Trenton, in the State of New Jersey, have invented a new, original, and ornamental Design for Rubber Bindings for Matting Ends or Similar Articles, of which the following is a specification, reference being had to the accompanying drawing, forming a part hereof.

The figure is a plan view of a short strip of rubber binding, showing my new design.

I claim:

The ornamental design for a rubber binding for matting ends or similar articles, as shown.

CLIFFORD H. OAKLEY.
